TOOTHPICK DISPENSER

William Essig, New York, N. Y.

Application March 21, 1936, Serial No. 70,126

1 Claim. (Cl. 312—84)

This invention relates to dispensers for toothpicks, matches and other similar objects and has for the primary object the provision of a portable, simple and efficient device which may be easily filled and actuated to dispense a single article at a time and is provided with means for adjusting the articles therein so that they will feed one at a time to the dispensing means of the device during each operation of said dispensing means.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a vertical sectional view illustrating a dispenser constructed in accordance with my invention.

Figure 2 is a front elevation illustrating the same.

Figure 3 is a sectional view taken on the line 3—3 of Figure 1.

Figure 4 is a fragmentary sectional view illustrating the dispensing roller of the device.

Figure 5 is a fragmentary transverse sectional view illustrating the dispensing roller and the means of directing articles thereto.

Referring in detail to the drawing, the numeral 1 indicates a container open at its upper end so that it may be readily filled with toothpicks, matches or similar articles and is normally closed by a hinged cover 2. The container is supported by spaced legs 3 secured to the side walls of said container. The legs project beyond the front face or wall of the container. The bottom wall of said container is arranged between the legs and includes inclined portions 4 and a discharge slot 5 located at the merger of said inclined portions, the latter acting to direct the toothpicks or like articles to the slot.

A dispensing roller 6 is journaled to the legs 3 and is located between the latter with a portion of the periphery projecting into the slot 5. The ends of the roller are provided with screw threaded bores to receive stud bolts 7 which extend through openings in the legs 3, thereby forming journals for the roller and which provides a construction whereby the roller may be readily removed from the device when desired. One of the stud bolts 7 has formed integrally therewith a lever 8 terminating in a laterally extending finger piece 9. Said last-named stud bolt is engaged by a set screw 10 threaded to the roller 6 for locking the stud bolt to said roller.

Arranged longitudinally of the roller within its periphery is a groove 11 which when within the slot 5 will receive a single toothpick or like article and as shown in Fig. 5 the roller has an

eccentric or outwardly extending cam portion 11' at one side thereof. A movement of the lever 8 in one direction causes rotation of the roller 6 in the direction indicated by the arrow in Figure 5 to position the groove 11 into emptying position so that the toothpicks or like articles will gravitate onto a shelf 12 carried by the legs 3 so as to be easily obtained by the person operating the device. A counter balance weight 13 is secured to the roller and acts to restore the roller 10 in a position when the lever 8 is manually released so that the groove 11 will lie in the slot 5 to receive another toothpick or similar article from the container.

V-shaped notches 14 are formed in the periphery of the roller and trail the groove 11 so that on said groove moving into discharging position the notches contact certain of the toothpicks in the container and thereby agitate the toothpicks whereby they will adjust themselves 20 for entrance into the groove 11 of the roller when said groove occupies receiving position.

A flexible strip 15 is secured to one of the inclined portions 4 of the bottom of the container and extends over the slot 5 to ride upon the peripheral cam portion 11' of the roller to vibrate 25 the same, whereby the articles within the container are kept from wedging between the walls and slot 5 and the periphery of the roller when the latter is actuated to position the groove from receiving position to discharging position. Also, in the event that the articles should become 30 entangled, the vibrating action of the strip 15 will serve to adjust said articles so that they will readily enter the dispensing groove of the roller. 35 The strip 15 further serves to close the space between the inclined wall and roller, as the roller is rotated.

Having described the invention, I claim:

A dispenser comprising a container having 40 positively inclined portions in its bottom and a discharge slot between said portions, a support for said container, a dispensing roller controlling the slot and supported adjacent thereto and having a groove to receive a single article at a time 45 from the container and to deliver said article, a lever operatively engaging said roller for imparting movement thereto in one direction, a counter balance weight secured to the roller for imparting a reverse movement thereto, a shelf 50 carried by said support to receive the article from the groove of the roller, said roller having notches trailing the groove to agitate articles within the container, said roller having an outward cam projection forward of the groove, and a flexible 55 strip secured to one of the inclined portions of the container and normally contacting the peripheral cam portion of the roller.
